SUPPLEMENTAL HEAT UNIT FOR GRAIN STORAGE BINS AND THE LIKE

Victor J. Muell, Des Moines, and Edwin C. Riggs, West
Des Moines, Iowa, assignors to Lennox Industries, Inc.,
Des Moines, Iowa, a corporation of Iowa

Filed Feb. 16, 1962, Ser. No. 68,861

Term of patent 14 years

(Cl. D81—20)

We claim:

The ornamental design for a supplemental heat unit for grain storage bins and the like, substantially as shown.
